UNITED STATES PATENT OFFICE.

ADOLPH WUNDER, OF NEW HAVEN, CONNECTICUT, ASSIGNOR TO SARGENT & CO., OF SAME PLACE.

DESIGN FOR A DOOR-LATCH.

Specification forming part of Design No. 5,766, dated April 9, 1872.

To all whom it may concern:

Be it known that I, ADOLPH WUNDER, of New Haven, in the county of New Haven and State of Connecticut, have invented a new Design for Door-Latch; and I do hereby declare the following, when taken in connection with the accompanying drawing and the letters of reference marked thereon, to be a full, clear, and exact description of the same, and which said drawing constitutes part of this specification, and represents, in—

Fig. 1, the plate; Fig. 2, the handle; Fig. 3, the latch; Fig. 4, the escutcheon for the reverse side of the door; Fig. 5, the guard; and in Fig. 6, the keeper.

This invention relates to a design for door-latches such as employ a handle upon one side, a lever extending through to operate the latch upon the opposite side.

The several parts composing the latch complete are shown in the several figures, but, as either of the parts may be used in connection with other parts differing from these—as, for instance, a different handle upon the plate, or

the handle and plate with different smaller parts—my design is not confined to the several parts combined, but to those parts individually or collectively; and it consists in the configuration and ornamentation of the parts, as shown in the accompanying illustration.

Around all the parts of the form shown a plain edge is raised, forming a panel on the surface; and the surface of the panel is ornamented by tracery, as shown in the illustration, raised in like manner as the edge, so that the tracery and edge may be polished, the ground of the panel being matted or otherwise finished, the raised edge and tracery denoted in solid black.

I claim as my invention—

The design for the parts of a door-latch, shown and described, whether used together or separately.

ADOLPH WUNDER.
